UNITED STATES PATENT OFFICE.

JOSEPH T. BARNES, OF MANAYUNK, PENNSYLVANIA.

POWER-LOOM.

Specification of Letters Patent No. 11,804, dated October 17, 1854.

To all whom it may concern:

Be it known that I, JOSEPH T. BARNES, of Manayunk, in the county of Philadelphia and State of Pennsylvania, have invented 5 certain new and useful Improvements in Power-Looms; and I do hereby declare that the following is a full, clear, and exact description of the same, reference being had to the accompanying drawings, forming 10 part of this specification, in which—

Figure 1, is a transverse vertical section of a loom having my improvements. Fig. 2, is a plan of the same. Fig. 3, is a side view of the belt shipper and the mechanism 15 connected therewith. Fig. 4, is a front view of one of the bearings of the main shaft with a section of part of the framing.

Similar letters of reference indicate corresponding parts in the several figures.

20 This invention consists in certain new arrangements and contrivances, whereby the forward or beating up movement of the lay is caused to be arrested by the sliding back of the journal boxes of the crank shaft of 25 the loom, in time to prevent injury to the cloth or the loom, when the shuttle is arrested in its flight outside the shuttle box, which said arrangements and contrivances also dispense with and perform the duty of 30 the protector commonly employed to throw the loom out of gear in case of such accidents.

It also consists in certain contrivances for returning the crank shaft to its operative position as soon as the loom is thrown in gear after the cause of stoppage is removed.

To enable those skilled in the art to make and use my invention, I will proceed to describe its construction and operation.

40 A, is the framing of the loom which is similar to that of other looms, except that the top parts of the side pieces are properly constructed to form ways *a*, *a*, upon which the journal boxes B, B, of the crank shaft C, 45 are capable of sliding back and forth, without working out of gear with the cam shaft D. These ways, to be properly constructed, should be in the form of arcs described from the axis of the shaft D, and their transverse 50 form should be that of a dovetail or any other form capable of preventing the journal boxes rising from them. The journal boxes are confined in their proper position for the operation of the loom by means of 55 two hooks *b*, *b*, which are pivoted, one to each bearing, and hook on to pins or projec-

tions *c*, *c*, in the inner faces of the side framing A, A, the said hooks being assisted by two springs *d*, *d*, which connect the boxes with the framing, and hold them back with 60 the hooks in contact with the pins.

E, is a rockshaft or roller hung in suitable bearings *e*, *e*, at the back of the breast beam, and carrying on its upper side two light arms, *f*, *f*, to which are attached a bar F, 65 of wood whose length is about equal to the width of the reed. This bar F, when the loom is at work, stands either above or below the cloth in such position that the race beam will just pass under it without touching, 70 and the face of the reed arrive within a very short distance of it, say one fourth of an inch when the filling is beaten up. The shaft or roller E, carries on its lower side two other L-shaped arms *g*, *g*, whose weight 75 causes one of them to rest at all times except when the bar F, is pushed forward upon a stud or projection *h*, on the inside of the framing. The ends of these arms are bent inward as shown at *i*, *i*, in Fig. 2, or 80 otherwise constructed to form lifting pieces *j*, *j*, to stand under the ends of the hooks *b*, *b*, with which they, when the arms *g*, *g*, are supported by the stud *h*, are nearly in close contact.

85 As long as the shuttle continues to enter the shuttle boxes, the journal boxes, and the shaft or roller E, and its appendages remain stationary; but if the shuttle fails to enter its box before the lay arrives near the bar F, the beating up brings the shuttle in contact with the said bar, and pushes it forward as shown in red outline in Fig. 1, thereby throwing up the lower parts of the arms *g*, *g*, and causing them to lift the hooks *b*, *b*, 90 from the pins or projections *c*, *c*, and set the journal boxes free to be drawn back by the springs *d*, *d*, which then act promptly. This drawing back of the journal boxes and crank shaft, although the revolution of the 100 shaft is not instantly arrested, not only prevents the further advance of the lay, but carries it a short distance back, even though the distance between the lay and the shaft continues to increase owing to the continuance 105 of the revolution of the shaft until the loom is thrown out of gear by the slipping of the belt, which is effected by a hooked rod G, which is attached to a spring shipper lever H, of the usual kind arranged in the usual 110 way. This hooked rod is slotted to fit and slide freely upon a pin *l*, in the outside of

the framing, so that when the hook *j*, at its end is caught by one of the journal boxes as the latter slides back it draws back the rod and draws the spring shipper lever from 5 its notch and sets it free to move in the required direction to ship the belt from the fast to the loose pulley.

The crank shaft is furnished near each journal box inside the framing with a cam 10 *I*, of scroll or other suitable form, which, when the belt is again shipped onto the fast pulley to set the loom in motion, is caused by the revolution of the shaft, to work in contact with a fixed pin or projecting piece 15 *m*, on the inside of the framing, and thereby throw the shaft and its journal boxes forward until the hooks, *b*, *b*, which by being extended in front of their catches, are caused always to rest on the pins or projections *c*, *c*, 20 fall over and catch on the said pins or projections, after which the crank shaft and lay are in proper condition for operation.

This invention, while it dispenses with the protector commonly employed and performs 25 the same duty effects what the protector does not, viz: setting free the reed, and allowing it to swing back when any obstruction occurs in front of it.

What I claim as my invention, and desire 30 to secure by Letters Patent, is:—

1. Fitting the journal boxes of the crank shaft to slide on ways on the framing upon which, when liberated by reason of some obstruction in front of the reed, they are

capable of being drawn back to carry back 35 the crank shaft from its operative position, and prevent the further advance of the lay, by springs or their equivalents, substantially as herein set forth.

2. Setting free the journal boxes of the 40 crank shaft from the hooks or their equivalents, which hold them in proper operative position, by means of a rock shaft *E*, or roller hung in bearings in rear of the breast beam, or otherwise conveniently placed near 45 the front of the loom, said shaft or roller having attached to it a bar *F*, which is conveniently placed for the breast beam to pass under it, and for the shuttle, when the latter is arrested in front of the reed, to be driven 50 against it and drive it forward, and thereby throw up two arms *g*, *g*, which are also attached to the shaft or roller, and cause the latter arms to set free the journal boxes of the crank shaft, and allow them to retreat 55 and carry back the shaft, substantially as herein set forth.

3. Furnishing the crank shaft with cams *I*, *I*, which, when the loom is started with the shaft thrown back, work in contact with 60 fixed pins or projections *m*, *m*, on the loom framing, and throw the shaft and its journal boxes forward to their operative position, as herein fully described.

J. T. BARNES.
